(57) **CLAIM**

The ornamental design for a burger smasher, as shown and described.

DESCRIPTION

FIG. 1 is a front-left perspective view of a burger smasher showing the new design;

FIG. 2 is a bottom-right perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left-side elevation view thereof;

FIG. 8 is a right-side elevation view thereof;

FIG. 9 is an exploded perspective view of the burger smasher;

FIG. 10 is another exploded perspective view thereof; and,

FIG. 11 is a front elevation view thereof.

The broken lines depict portions of the burger smasher that form no part of the claimed design.

1 Claim, 11 Drawing Sheets
